UNITED STATES PATENT OFFICE.

WILLIAM W. DEAN, OF ELYRIA, OHIO, ASSIGNOR, BY MESNE ASSIGNMENTS, TO THE GARFORD MANUFACTURING COMPANY, OF ELYRIA, OHIO, A CORPORATION OF OHIO.

TELEPHONY.

1,145,861.

Specification of Letters Patent.

Patented July 6, 1915.

Application filed August 6, 1909. Serial No. 511,577.

To all whom it may concern:

Be it known that I, WILLIAM W. DEAN, a citizen of the United States, residing at Elyria, in the county of Lorain and State of Ohio, have invented certain new and useful Improvements in Telephony; and I do hereby declare the following to be a full, clear, and exact description of the invention, such as will enable others skilled in the art 10 to which it appertains to make and use the same.

My invention relates more particularly to telephone casings and especially to telephone desk sets and the details thereof.

15 Some of the objects of my invention are to provide a desk set, all of the parts of which are rigidly connected to one another, thus avoiding the use of unnecessary pivot connections between the various frame 20 parts; to provide a convenient arrangement for associating the switch hook and the contacts controlled thereby with the casing in such a way that they are accessible to the workmen; to provide connections between 25 the various parts of the casing in such a way that they do not interfere with the cleaning of the exterior of the casing, and at the same time those which are operable may be accessible from the exterior of the 30 casing. I have endeavored to produce such a desk set by connecting the various casing parts and to reduce the number of these parts to as few as possible, making a cheap, compact and easily constructed set.

35 In desk stands now in use, the transmitter and mouthpiece are pivoted to the standard. In eliminating this I construct my desk stand so that the front of the transmitter is inclined at an acute angle to the vertical; 40 that is, a line drawn through the face of the front to intersect a line drawn through the axis of the standard, intersects the same, making the angle nearest the instrument less than a right angle. I have so inclined this 45 front for the purpose of making the mouthpiece convenient to one who seated at a desk, uses the telephone. Of course the inclination of the front may be changed to suit different conditions and for different positions of use. For the general use to which 50 desk sets are placed they are either set on a desk and talked to or held in the hand. In the former case, the stand setting on the desk presents the mouthpiece below the 55 mouth of the user; in the latter, the user

holds the stand so as to receive some support therefor from the chair or his body in which position the telephone mouthpiece will be below his mouth. To meet these contingencies I incline the front of the 60 transmitter and the mouthpiece upward as shown.

My invention will be best understood by reference to the following description when taken in connection with the accompanying 65 illustration, showing one specific embodiment thereof, while its scope will be more particularly pointed out in the appended claims.

In the drawing, Figure 1 is a cross-section 70 through the desk set showing the arrangement for supporting the telephone apparatus therein and the connection between the various parts of the casing. Figs. 2, 3, 4, 5, and 6 are details of the casing showing the 75 means for connecting the detachable parts to the casing proper.

1 is the hollow base to which the vertical standard portion 2 is attached. In the drawing these parts are shown as drawn 80 from the same piece of metal.

3 is an enlarged hollow casing adapted to house part of the telephone apparatus attached to the upper part of the tubular casing. The parts as shown in the drawing 85 are united so as to form a single compartment for the apparatus, each part communicating with the others, either directly or through the hollow standard. By eliminating partitions I lighten the set and facilitate 90 the running and making of the circuit connections. In the form shown in the drawing the standard 2 is extended into a narrow finger piece 17, and the enlarged casing 3 attached thereto by the screws or rivets 18 95 which make a rigid connection between these parts. A hollow portion projects from the hollow casing and, in the form shown, telescopes with the standard, being rigidly connected therewith. The front of the enlarged 100 casing is inclined at an angle to the standard 2, and a front piece 4 carrying the mouthpiece 5 is adapted to be detachably connected thereto to close the front of this casing. An inverted cup 6 is fastened in the 105 base of the set. A cover 7 is adapted to be detachably connected to close the mouth of the cup 6. An annular angular ring 14 is shown bent over the edge of the cup. An annular rubber ring 8 is inclosed between the lower 110

edge of the base and the set and this angular ring, furnishing a resilient buffer for the desk set. The bottom 7 of the cup is fastened thereto by a hook 35 which fits over the angular ring as shown in the drawing, and a rotatable catch member 13 which engages the annular ring 14 as a counterpart or coöperating catch member when the member 13 is rotated to engaging position. A recess 12 is made in the plate 7, and a slot 11, in the rotatable member 13. The rotatable member 13 is inclosed in a casing 9 which is attached to the bottom piece 7 and within which the member 13 rotates. Shoulders 36 and 37 are shown on the casing 9. These shoulders limit the movement of the catch 13 to engaging position with the counterpart catch member on one side and to complete disengaging position with the said catch member on the other side. A screw driver or similar tool may be inserted through the recess 12 into the slot 11 to rotate the member 13 in order to lock or release the bottom to or from the cup. The terminals 15 are mounted in the base of the casing and the conductors 16 extended through the standard portion to the contacts which are included in the enlarged hollow casing. The front of the enlarged upper casing portion is connected thereto by a joint and catch arrangement very similar to that just described. A catch hook 46 and a counterpart catch member 45, the former attached to the front, the latter to the casing, are arranged to hook over each other when the front is placed upon the casing.

At 19 I show a catch housing attached by rivets 32 to the enlarged upper casing portion. A hook catch member 21 is inclosed within this casing to rotate between abutments 38 and 39 formed on the casing 19 and which limit the rotation of the hook. The hook catch 21 is bent upward at 50 and extended into a hook 30. A slot 22 is cut in the base of the hook catch and coöperates with the recess 20 in the casing 3. The hook engages with a counterpart catch member 31 formed on the front piece. In the drawing this piece is shown in the form of a tongue cut from the front itself and bent upward. A tool may be inserted through the recess 20 into the slot 21 and the hook rotated between the limits of the abutments which confine the movement from full engagement position between the catch members and position of complete disengagement. It will be seen that I thus provide means for connecting these detachable parts which are located entirely within the casing and which may be operated to quickly and easily unlock the catches by means inserted from without the casing.

The transmitter bridge bearing a transmitter and attached to the casing front is

shown at 23. I show a bracket 40 attached at 24 to the standard portion and extending upward into the enlarged part of the casing. The switch hook 43 is pivoted at 42 to said bracket. The contacts 25 and 41 and a hook controlling spring 44 are also carried by this bracket. The switch hook 43 controls the connection and disconnection of the springs 25 and 41. The contact springs and the switch hook arrangement and other apparatus carried by the bracket, can be easily reached by removing the front 4.

I thus provide a desk set which is simple, and compact. The telephone apparatus is inclosed in the two extremes of the set and the portions in each extreme may be readily reached by removing the detachable portions at the top and bottom of the casing. These detachable portions are not attached by any complicated locking mechanism, and yet this locking mechanism is of such nature that it cannot be operated without the use of some tool. It is simple of construction and easy to operate, so that the apparatus inclosed within the casing can be quickly and easily approached.

While I have shown and described this particular form of my invention which is my preferred form, it will be obvious to those skilled in the art that numerous and extensive departures from the form and details of the apparatus thus shown, may be made without departing from the spirit of this invention, the same being herein shown solely for the purpose of clearly illustrating one specific embodiment thereof.

I claim:

1. In a telephone desk set, the combination with a base, a hollow standard portion supported by said base, a hollow casing, a hollow open portion projecting from said casing and rigidly attached at its open end to the standard, telephone apparatus housed in said casing, a front for said casing adapted to be detachably connected to said hollow casing and a mouthpiece on said front, said front when so connected inclined at an angle to the standard so that the mouthpiece is tilted with the mouth thereof opening upward.

2. In a telephone desk set, the combination with a base, of an upright standard portion supported by said base, a hollow casing, a hollow open tubular portion extending from said casing and rigidly connected to said standard, said hollow casing curved over to present a front at an angle to the standard, telephone apparatus housed in the casing, a front detachably connected to said casing and a mouthpiece on said front, said front when connected to the hollow casing being so inclined that the mouth of the mouthpiece opens upward.

3. In a telephone desk set casing, the com-

- bination with a base, a hollow standard supported by said base, a housing attached to the upper end of said standard, a removable cover for said housing, a bracket mounted in 5 said hollow standard extending into the housing, a switch hook pivoted to said bracket, switch contacts controlled by said switch hook mounted within the housing, said parts being thus inclosed by said housing, and said switch hook pivot and switch contacts being exposed and accessible when the cover is removed.
4. In a desk set, the combination of a base, a standard portion supported by said base, 15 a finger extending from the upper part of the standard portion, a hollow casing adapted to telescope with said standard portion and rigidly connected to said finger, and a casing front for said hollow portion.
5. In a telephone desk set, the combination of a base, a mouthpiece, a hollow standard casing supported thereon, a second hollow casing rigidly supported on said standard, a removable cover for said second casing 20 carrying said mouthpiece, a bracket supported within said casings and behind said removable cover, a switch hook pivoted to said bracket and a plurality of springs carrying contacts controlled by said switch hook and mounted on said bracket, said switch hook pivot and said contacts being exposed and 25 accessible when said cover is removed.
6. In a telephone desk set, the combination of a rigid hollow tubular casing, a removable cover therefor, a mouthpiece supported from said cover, a bracket supported from the inner wall of said tubular casing, a switch hook lever pivoted to said bracket under said cover, a plurality of contact 30 springs mounted on said bracket and contacts on said springs controlled by said lever, said lever pivot and said contacts being exposed and accessible when said cover is removed.
7. In a desk set, the combination of a base, a tubular portion supported by said base, an enlarged hollow casing supported by the tubular portion, a bracket attached to said tubular portion and extending into the enlarged casing, a switch hook pivoted to said bracket, spring contacts carried by said bracket and controlled by said switch hook, and a front for said casing.
8. In a telephone desk set, the combination 45 with a base, a hollow standard supported by said base, an enlarged casing rigidly attached to said standard, a bracket mounted in said standard and extending into the enlarged casing, a switch hook pivoted to said bracket, switch contacts controlled by said switch hook mounted on said bracket, and a front for said enlarged portion.
9. In a desk set, the combination of a base, a hollow standard supported by said base, an enlarged casing connected to said standard, a bracket attached to said standard and extending into said enlarged casing, a switch hook pivoted to said bracket and extending through a slot to the exterior of the casing, contact springs carried by said bracket and controlled by the switch hook, a front for 50 said casing, means located within the casing for locking the front to said casing, said means being operated from without said casing.
10. In a telephone desk set, the combination of a rigid cylindrical hollow casing, a removable cover controlling the entrance into the top of said casing, means accessible from the outside of the casing for removably 55 connecting the casing cover to the casing, a mouthpiece mounted on said casing cover, a bracket mounted within the walls of said casing, a switch hook lever pivoted to said bracket, a plurality of switch springs mounted on said bracket, said switch hook lever pivot being under said cover, contacts on said springs controlled by said lever, and said bracket remaining with said casing and said switch hook pivot, and said contacts 60 being exposed, when said cover is removed.
11. In a telephone desk set, the combination of a rigid standard casing having an opening in the top thereof, a base supporting said casing, a removable cover controlling the entrance to said standard casing, a mouthpiece mounted on said cover, means accessible from the outside of said casing and cover for removably connecting the cover to the casing, a bracket connected to 65 said casing on the inside thereof, a switch hook lever pivoted to said bracket under said cover, a plurality of switch springs in said casing and contacts on said springs controlled by said lever, said switch hook pivot and said contacts being exposed when said cover is removed and means to connect said cover to said casing.

In testimony whereof I affix my signature in presence of two witnesses.

WILLIAM W. DEAN.
